TO KELVINATOR CORPORATION, OF WILMINGTON, DELAWARE, A CORPORATION OF
DELAWARE.

THERMOSTAT.

1,416,722.

Specification of Letters Patent. Patented May 23, 1922.

Application filed March 21, 1919. Serial No. 284,039.

To all whom it may concern:
Be it known that we, FREDERICK H. KOLBE and EDWARD R. DE LUIZ, citizens of the United States, residing at Detroit, in the county of Wayne and State of Michigan, have invented a certain new and useful Improvement in Thermostats, of which the following is a full, clear, and exact description, reference being had to the accompanying drawings.

This invention relates to thermally controlled electric switches. It is capable of many uses, but is especially designed for use in connection with a refrigerating apparatus, and has for its object to provide an improved device in which an electric switch is controlled by temperature conditions in the apparatus, and this switch in turn controls an electric motor which drives the compressor of said apparatus, the motor being started or stopped according to predetermined conditions.

The objects of the invention are the provision of a simple and compact device which while small in total size shall possess an extremely large operating chamber; the provision of a thermostat of the volatile fluid type which shall combine the possession of a large volume of the volatile agent whereby a powerful action is produced, large exposed surface whereby promptness of operation is secured, and provisions whereby its motion is restrained to a small compass so as to prevent injury by extremes of temperature above or below the range for which it is intended. Other objects are the provision of a device which is easily and simply manufactured, easily adjusted and free from disorders; the provision of improved means for associating it with the surrounding and co-operating objects; while further objects and advantages of the invention will become apparent as the description proceeds.

In the drawings accompanying and forming a part of this application we have illustrated certain physical forms in which our invention may be embodied although it will be understood that these drawings are intended to be illustrative only and not to limit us to the particular details therein shown. In these drawings Fig. 1 is a vertical sectional view of one form of the device corresponding approximately to the line 1—1 of Fig. 3; Fig. 2 represents a side ele-

vation of the same device, the switch block 55 being shown in section; Fig. 3 is a top plan view of the device shown in Fig. 1; Fig. 4 is a vertical sectional view showing a modification; and Fig. 5 is a detail view showing the preferred mode of applying our improved thermostat to a refrigerating apparatus.

Referring first to Fig. 5, we have for purposes of illustration shown a corner of an ordinary domestic refrigerator having a brine tank and cooling coil located in the chamber ordinarily provided for ice. This refrigerator comprises an external rectangular casing 1 having therein an upright partition 2 spaced from the top as shown to provide an air passage 3, and also spaced from the bottom (not shown) to provide another passage in the well known manner. The chamber 4 defined at one side of the partition 2 is employed for the storage of food, and the chamber 5 at the other side of said partition constitutes a refrigerant space the upper part whereof is ordinarily employed for ice which is supported upon a partition 5a in such wise that the circulating air can pass over and around the same.

In this ice space we have shown a metal brine tank 6 having therein an upright pipe coil 7 through which is pumped the refrigerant fluid, which preferably consists of a low boiling point fluid. The upper part of this coil is preferably constricted in size as shown at 8 to form a space for the reception of our improved thermostat. It will thus be seen that the upper end of the exposed portion of the coil is the part first contacted by the air which enters through the passage 3, and the uppermost turns of the coil are preferably located closely adjacent to each other so that this entering air shall have very little direct access to the thermostatic vessel. The device shown in Figs. 1 to 3 includes a supporting cap 10, circular in plan, and of proper size and shape to fit upon the top of the coil 8, by which it is supported. This cap has a spiral peripheral flange 11, which fits upon the upper convolution of the coil, the angle of the flange 11 corresponding to the pitch of the coil, so that the cap will rest flatly thereon, and be supported with its axis substantially vertical. This cap also prevents direct impingement of the entering air upon the thermostatic vessel.

This cap has a plurality of depending fingers 12 on its under side, the lower ends of which form abutments for the top plate 13 of an expansible vessel 14. This vessel is of the well-known metallic bellows construction, comprising a circumferentially-corrugated, longitudinally-expansible, cylindrical sheet metal wall with rigid ends forming a closed receptacle for volatile fluid. The lower wall of the vessel is indicated at 15 and has secured to it the rods 16 by which it is connected to the arms of a movable spider 17 which is located between the cap 10 and the top wall 13, said arms projecting between the fingers 12. The head 17 carries a rod 18, which works through a hole in the cap 10, and has a collar 19 to limit its downward movement. The rod is threaded as indicated at 20, above the collar, and this threaded part receives a nut 21 to which is fixed the lower end of a coil tension spring 22, the upper end of which is fixed to a collar 23 which may be turned in its seat in a cap 24 fitting upon the upper end of a spacing tube 25, which encloses the spring and which rests at its lower end upon the top of the cap 10, the upper end of the rod 18 passing freely through an opening in the collar 23.

The upper end of the rod 18 is pivoted at 26 to a lever 27 which is fulcrumed at 28 to a bracket 29, supported on the casing. The outer end of the lever is forked as shown at 30, and engages a slot 31 in an adjustable nut 32 to which is attached the screw rod 33, which reciprocates through the top of the switch casing 34. The lower end of this rod is operatively attached to the switch mechanism so as to close the circuit when it is depressed and open the circuit when it is elevated. Any suitable or convenient kind of switch mechanism can be employed, wherefore I have not indicated any detail construction except that the same is preferably housed in a hollow casing 34 of insulating material mounted on an extension 35 at one side of the cap 10 and connected to the lead wires 36 by means of a separable plug 37. In the construction shown in Fig. 1 the cap 24 is extended to cover and embrace the switch casing 34 as well as the tube 25 and is apertured for the reception of a boss 38 formed on that casing. The bracket 29 is also apertured for the same boss, while the bracket, cap, tube, and casing are all held in place by the single screw 39. This detail construction is not, of course, essential to our invention but it is valuable in practice.

In the modification shown in Fig. 4 the construction is similar, except that a compression spring 22^a is used, instead of the tension spring 22. This has some advantages as a compression spring is easier to adjust. This compression spring is confined

between the top of the cap 10, and a nut 21^a adjustable on the screw rod 18^a, and movable freely inside the tube 25^a which is here shown as integral with the cap.

In the operation of the device the expansion or contraction of the expansible vessel is transmitted through the rods 16 to the head 17, rod 18 and lever 27 to the movable switch member, and when the device is properly set according to the temperature desired, the motor circuit will be opened by the spring 22 when the vessel contracts a predetermined amount owing to the decrease in vapor tension inside the vessel, and closed by its expansion or increase of such vapor tension, beyond the ability of the spring to withstand it. The expansion and contraction of the vessel is therefore always restricted within a narrow range and operation of the switch occurs at the same points, the temperature of such operation depending upon the tension of the spring 22. In the form shown in Fig. 1 this tension may be varied by turning the collar 23 which rotates the spring 22 and with it the nut 21 which rides up or down on the rod 18 accordingly. In the form shown in Fig. 4, the rotation of the nut 21^a acts upon the spring directly.

Extremes of temperature have no injurious effect, either upon the vessel or upon the spring; for upon excessive heat, the expansion of the vessel is arrested by the collar 19 at a point within the elastic limit of the spring and upon excessive cold, the contraction of the vessel is arrested by the fingers 12, the spring being absolutely freed from strain. The last named feature is particularly important in a thermostat for refrigeration use as rendering it safe against high temperatures which may occur either through accidental failure of the operating current or by reason of shipment, installation, or adjustment in hot weather.

The cap 10 serves to protect the expansion chamber from the direct impact of the inflowing warm air and restricts the heat exchange largely to the side walls of the same. As a consequence, during the operation of the refrigerating motor (not shown) the brine tank 6 will first become very thoroughly cooled after which the coil 7 will become covered with frost up to and surrounding the vessel 14 whereupon sufficient heat will be abstracted from that vessel to reduce the vapor pressure of the fluid therein and permit the spring 22 to open the switch and stop the motor. The shielding effect of the coil 8 and cap 10 prevents the thermostat from absorbing an amount of heat necessary to expand the vessel and close the switch until the coil 8 has become quite thoroughly warmed up, undue elevation of the temperature in the provision chamber 4 being meanwhile prevented by the large heat

capacity of the brine tank 6. As a consequence of this general construction and arrangement we have been able to increase very markedly the length of the idle periods 5 of the motor and thereby save operating cost without endangering the refrigerating capacity of the machine. Also as above stated the large volumetric capacity of the vessel 14 leads to a very prompt and positive 10 operation while the features of construction which have been specifically pointed out prevent injury of the device by excessive temperatures. We have shown the bottom plate 15 as provided with a filling opening closed 15 by a screw-plug 40.

We do not restrict ourselves to the detail constructions herein shown except as recited in the claims and necessitated by the prior art.

20 Having thus described our invention, what we claim is:—

1. The combination of a supporting plate having on one side a plurality of spaced abutments, a longitudinally expansible vessel having one end presented against said abutments, a head located between said plate and vessel and having cavities for said abutments, connecting means between said head and the further end of the said vessel, a controlling device mounted upon the opposite side of said plate, and operative connections between said head and controlling-device.

2. In a device of the character described, in combination, a pair of interfitting, relatively movable members, one having abutments and the other connecting devices, a longitudinally expansible vessel having its nearer end engaging said abutments and its further end connected to said connecting devices, a controlling device carried by one of said members and operatively connected to the other member, and a single spring adapted and arranged to oppose such movement between said members as occurs upon the 45 elongation of said vessel.

3. The combination of a cap having depending projections on its under side, a head movable up and down between said projections, an expansible vessel abutting at one 50 end against said projections, connections between the other end of the vessel and the head, an electric switch mounted upon the cap, and an operating connection between said head and the movable member of the 55 switch.

4. The combination of a cap having depending projections on its under side, a head movable up and down between said projections, a longitudinally expansible vessel 60 abutting at one end against said projections, connections between the other end of the vessel and the head, an electric switch mounted upon the cap, and an operating connection between said head and the movable member 65 of the switch, said connection including a

rod extending through the cap, and a spring connected to the rod and tending to contract the vessel.

5. The combination of a cap having spaced abutments on one side thereof, a longitudinally extensible cylindrical vessel one end of which is seated against said abutments, a head movable axially with respect to the cylinder between the abutments, a connection outside the cylinder between the other end thereof and the head, a rod projecting from the head through the cap, a spring attached to the rod and tending to contract the vessel, a switch supported on the opposite side of the cap, and an operating connection between the rod and the switch.

6. The combination with a circumferentially corrugated, longitudinally expansible, cylindrical, sheet-metal vessel having sealed ends, of a head overhanging and spaced from one of said ends, connecting means between said head and the opposite end, a support located above and spaced from said head, abutments carried by said support and engaging the first mentioned end of said vessel, 90 an operating rod attached to said head, spring means connected to said rod and support and opposing the elongation of said vessel, a controlling device carried by said support, and operative connections between 95 said rod and device.

7. The combination with a circumferentially corrugated, longitudinally expansible, cylindrical, sheet-metal vessel, having sealed ends, of a head overhanging and spaced from one of said ends, connecting means between said head and the opposite end, a support located above and spaced from said head and having a hole over said vessel, abutments carried by said support and engaging said vessel, a rod connected to said head substantially coaxial with said vessel and passing through said hole, a spring operatively connected to said rod and opposing the expansion of said vessel, a controlling device carried by said support, and operative connections between said rod and device.

8. The combination with a circumferentially corrugated, longitudinally expansible, cylindrical, sheet-metal vessel having sealed ends, of a head overhanging and spaced from one of said ends, tension means connecting said head with the opposite end, a support located above and spaced from said head and having a hole over said vessel, abutments 115 carried by said support and engaging said vessel, a rod connected to said head substantially coaxial with said vessel and passing through said hole, engaging projections carried by said rod and support for limiting the expansion of said vessel, a controlling device carried by said support, and operative connections between said head and device.

9. In combination, a cap having a hole and 130

a plurality of fingers arranged around said hole, a head having cut-away portions for the passage of said fingers, a rod connected to said head and passing through said hole, connected to said rod and opposing the extension of said vessel, and an electric switch 10 operatively connected to said rod.

5 a vessel which is expansible in the direction of said rod having one end seated against said fingers and having its opposite end connected to said head, adjustable spring means

In testimony whereof, we hereunto affix our signatures.

FREDERICK H. KOLBE.
EDWARD R. DE LUIZ.
